(57) **CLAIM**

The ornamental design for a ceiling fan light kit as shown and described.

DESCRIPTION

This application is also related to U.S. Design patent application Ser. Nos. 29/722,707 and 29/722,726.

FIG. 1 is a top perspective view of a first embodiment of a ceiling fan light kit;

FIG. 2 is a bottom perspective view of the ceiling fan light kit of FIG. 1;

FIG. 3 is a top view of the ceiling fan light kit from FIGS. 1 and 2, shown without the surrounding ceiling fan environment;

FIG. 4 is a bottom view of the ceiling fan light kit of FIG. 3;

FIG. 5 is a right side view of the ceiling fan light kit of FIG. 3;

FIG. 6 is a left side view of the ceiling fan light kit of FIG. 3;

FIG. 7 is a front view of the ceiling fan light kit of FIG. 3; FIG. 8 is a rear view of the ceiling fan light kit of FIG. 3; FIG. 9 is a top view of a variation of the ceiling fan light kit from FIG. 3 to form a second embodiment;

FIG. 10 is a bottom view of the second embodiment;

FIG. 11 is a right side view of the second embodiment;

FIG. 12 is a left side view of the second embodiment;

FIG. 13 is a front view of the second embodiment; and,

FIG. 14 is a rear view of the second embodiment.

Portions of the ceiling fan light kit and the ceiling fan environment shown in broken lines form no part of the claimed design.
